CLAIM

The ornamental design for a bracelet, as shown and described.

DESCRIPTION

FIG. 1 is a perspective view of a bracelet; FIG. 2 is a front elevational view thereof; FIG. 3 is a rear elevational view thereof; FIG. 4 is a top plan view thereof; FIG. 5 is a bottom plan view thereof; FIG. 6 is a left side elevational view thereof; and, FIG. 7 is a right side elevational view thereof. The broken lines shown in the drawings represent portions of the bracelet and form no part of the claimed design.
